UNITED STATES PATENT OFFICE

2,005,055

ELECTROLYTIC DEVICE

Robert C. Sprague and John F. McCann, Williamstown, Mass., assignors to Sprague Specialties Company, North Adams, Mass., a corporation of Massachusetts

Original application April 22, 1932, Serial No. 606,943, now Patent No. 1,997,185, dated April 9, 1935. Divided and this application May 8, 1934, Serial No. 724,592. In Canada September 19, 1932

2 Claims. (Cl. 175—315)

Our invention relates to electrolytic devices and more particularly to improvements in the construction of electrolytic condensers.

The present application is a division of our application Ser. No. 606,943, filed April 22, 1932 now Patent No. 1,997,185, and relates to certain venting means described in said prior application.

One object of our invention is to provide a condenser in which the component parts are of simple and inexpensive mechanical construction, and are adapted to be easily and quickly assembled.

Another object is to provide a novel vent for the escape of the gases formed during the operation of said condensers.

In the appended drawing:

Figure 1 is a vertical sectional view of a condenser embodying our invention.

Fig. 2 is a vertical section of the capped end of the container.

Fig. 3 is a perspective view of one end of the condenser.

As shown in Fig. 1, the condenser comprises a cylindrical metallic container 10, which preferably constitutes the cathode of the condenser and is provided at one end with a reduced neck or tubular extension 11. A seal provided in such tubular extension consists of a plug 12 of rubber or other resilient material, filling and extending slightly to the inside of and beyond the outer end of the tubular extension 11.

The plug 12 is provided with a central bore 12a through which protrudes an extension 15 of an anode assembly 16, said extension being secured in place by crimping the sides of the neck 11 diametrically opposite each other as at 13—13, whereby the said plug thus forms a liquid and gas tight seal between the neck 11 and the plug 12, and also about the extension 15 of the anode assembly. This crimping of the neck 11 about the plug 12 may be accomplished by spinning, squeezing, and other well-known means, and the word "crimping" in the claims should comprise such modification.

The container is almost completely filled with a suitable liquid electrolyte 27.

The other end of the container is provided with a circular cap 20 preferably of metal, the mid-portion of which forms a cup-shaped depression 21, which fits inside of the container 10 at 22. A washer shaped piece of wax-impregnated cloth 25' is interposed between the inside of the container 10 and the cap 20 (Fig. 2). The free edge of the cap 20 with the cloth 25' inter-

posed, is preferably spun over a rim provided on the container and which is perpendicular to its axis.

The minute pores or holes in the cloth 25' afford escape for the gas accumulated in the container during operation of the condenser, while the wax with which the cloth is effectively impregnated prevents leakage of the liquid electrolyte.

The anode assembly 16 which is supported in 10 the plug 12 by means of its extension 15, comprises a frame 17 having an inverted U shape. The anode proper consists of aluminum foil 18 of relatively small thickness which is folded back and forth upon itself in the manner of accordion pleating, and riveted or otherwise secured to the legs of the U shaped member at 19—19.

By this method of folding of the anode a considerable length of foil may be compactly placed in a small space, thus providing an anode of 20 large capacity. At the same time a relatively thin aluminum foil of the order of thickness of only 2 to 3 thousandths of an inch, can be used as its efficient support, and stiffening by the frame 17 makes it unnecessary to impart such rigidity 25 to the aluminum foil as to make it self-supporting.

To properly center the anode assembly there is provided on the upper end of the frame 17 a properly perforated insulating washer 28 of mica 30 or other suitable material which contacts with its edges with the container wall and thereby maintains the anode assembly in proper spaced relation to the latter. Instead of using for the spacing of the anode assembly a washer 28 as 35 above described, the anode assembly may be encircled by suitable insulating bands 29—29, for instance, of rubber.

Should it be found desirable to impart a greater degree of rigidity to the anode 18 than is afforded by the bands 29—29, a punched strip 55 of thin hard rubber or celluloid adapted to slip over the anode 18 is used. The strip 55 is provided with two lugs 56—56 which lie along the edges of the frame 17, and a slot 57 which permits the strip to be placed over the anode assembly 16. The strip 55 is flexed to enter the container 10, whereby the sides of the slot 57 support the foil 18 and keep its edges in alignment.

It should be noted that the extension 15 is 50 preferably an integral portion of the frame 17, thereby affording a very simple construction. Outside terminals can be easily attached to the extension 15. For instance, the extension may be provided with a hole 15a through which a 55

wire may be conveniently threaded or a metal connecting strip may be riveted, or the extension itself may form a threaded terminal to be provided with a nut.

5 5 In addition to the anode proper 18 being of aluminum or other film-forming metal, the frame 17 and its integral extension 15 is also of such metal. The container 10 may be of filming or non-filming metal.

10 10 It should also be noted that the amount of electrolyte and the disposition of the anode is so selected that the whole effective anode is submerged in the electrolyte in both horizontal and vertical positions of the condenser, thereby the 15 anode assembly is preferably so disposed that its lower and upper edges are equi-distantly disposed respectively from the bottom and the top of the container, and that sufficient space is left between the side edges of the assembly and the 20 wall of the container.

The condenser of our construction is adapted to be mounted both vertically and horizontally, or in any intermediate position.

It should be noted that even in a horizontal 25 position some portion of the cloth 25' (namely that portion which is uppermost and thus uncovered by the electrolyte) will permit escape of the gases formed in the container during operation of the condenser.

30 30 While we have described our invention on hand of specific construction and illustrated an elec-

trolytic condenser having a liquid electrolyte, it should be well understood that our invention is applicable in full or in part to other electrolytic condensers, as well as other electrolytic devices in general, and therefore the appended claims should be construed as broadly as permissible in view of the prior art.

5 What we claim as new and desire to secure by Letters Patent is:

1. An electrolytic condenser comprising a metallic container open at one end, a film-forming electrode in said container, and a liquid electrolyte in said container in which gases are developed during the operation of the condenser, a cap member for the closure of said open end of the condenser, and a finely meshed cloth washer impregnated with wax between said cap and said container, said washer permitting the escape of the gases, but being impermeable for the liquid electrolyte.

10 10 15 20 25 2. An electrolytic condenser comprising a cylindrical metallic container open at one end, and a metal member adapted to substantially close said open end, said container and said metal member forming a narrow gap between their opposing edges, and a finely meshed wax-impregnated cloth washer filling out said narrow gap, said washer permitting the escape of gases, but being impermeable for the liquid electrolyte.
